[57] CLAIM

The ornamental design for a baby blanket, as shown.

DESCRIPTION

FIG. 1 is a top plan view of a baby blanket showing my new design;

FIG. 2 is a bottom plan view thereof;

FIG. 3 is a front elevational view thereof; and,

FIG. 4 is a rear elevational view thereof.

The partial fragmentary cloth pattern, in FIGS. 1 and 2, is understood to extend throughout the area.

FIG. 1

FIG. 4
